LOAD DIVIDERS FOR GOODS CONTAINING COMPARTMENTS, SUCH AS THOSE OF CARRIERS

Gerald M. Magarian, Long Beach, and Paul K. Beemer, Laguna Beach, Calif., assignors to Preco Incorporated, Los Angeles, Calif., a corporation of California

Filed May 12, 1960, Ser. No. 28,793

16 Claims. (Cl. 105—376)

This invention relates to movable load dividers generally applicable to the interiors of freight carrying vehicles such as railway freight cars, automobile truck or trailer vans, or freight carrying vessels or aircraft, or, in fact, to any goods containing compartments. Although its applicability is general, the invention will be described in a preferred illustrative embodiment as applied to railway freight cars.

The general objective of the invention is to provide a simple, strong and strongly supported structure easily movable to various positions to form whole or partial dividing walls or bulkheads and storable when not in use against a wall or walls of the car. The general features of an illustrative embodiment, accomplishing those and other desired objectives, are typically described.

As applied to a railway car or similar carrier having a generally elongate freight compartment enclosed by floor or deck, side and end walls, and usually but not necessarily by a roof or ceiling, the invention utilizes upper and lower longitudinal rail structures at one or both side walls having longitudinal gear-rack formations. A vertical carrier shaft extends between the upper and lower rail structures, carrying two fixed gears of equal pitch diameters meshing with the racks. The carrier shaft is movable along the lengths of the rails, and the meshing gears maintain it parallel to itself in its various longitudinal positions—in the instance of a railway car with vertical side walls, maintain it always in vertical position.

A vertical wall or bulkhead member, here called a gate, is pivotally hung at one vertical edge on the carrier shaft by journaling which allows the gate to swing about and preferably to move vertically on the shaft, and allows shaft rotation for movement of the shaft and gate longitudinally of the rails. Although a single gate may, in transverse position, extend clear across the freight compartment, it is preferred for reasons such as gate strength against load impact and versatility of load dividing positions, that a single gate extend only part way across the compartment, with a similarly hung gate at the opposite wall.

In any selected transverse position, the swinging edge of the gate is locked against longitudinal displacement. That locking may be at both its upper and lower edges; but for purposes of simplicity is at only one of those edges and preferably at the lower edge where it is locked to the floor. That preferred locking arrangement also makes the present divider structures applicable to open-topped carriers of all types. In any such position, the pivoted edge of the gate is locked to one or both wall-rails. If locked only to one, the carrier shaft, then held longitudinally immovable at that one rail, holds the whole pivoted gate edge immovably. It is preferred, however, to lock the pivoted edge to both rails so as not to depend on the torsional strength of the carrier shaft for holding the, e.g., upper part of the pivoted edge if, say, only the lower part is locked to its rail.

In preferred form, the gate in its transverse wall- or bulkhead-forming position is thus locked at three corners. That makes for simplicity in the locking mechanism, in comparison, for instance, with locking at the upper swinging corner as well as at the lower.

2

In the preferred illustrative embodiment described in the following and shown in the accompanying drawings, the gate, as before stated preferable, is vertically movable on the carrier shaft and has its lower edge locked in either operative transverse or stored positions by simply lowering it. Its upper edge is then locked, preferably only at the pivoted corner, by a projectible locking pin actuated in conjunction with the mechanism by which the gate is raised and lowered. To move the gate, it is raised to clear the floor and then moved and swung to any desired position where it is again locked by the simple operation of lowering it.

Many other detailed features and accomplishments of the invention will appear from the following detailed descriptions of the present preferred and illustrative embodiment shown in the accompanying drawings, where:

FIG. 1 is a schematic plan showing typical positions of the load divider gates in a car;

FIG. 2 is an enlarged cross-section taken as indicated by line 2—2 on FIG. 1;

FIG. 2a is a schematic fragmentary elevation in the aspect indicated by line 2a—2a on FIG. 1;

FIG. 3 is a further enlarged horizontal section on line 3—3 of FIG. 2;

FIG. 4 is a further enlarged fragmentary section, on a vertical plane, of the upper parts shown in FIG. 2 and in the same aspect as in that figure;

FIG. 5 is a section on line 5—5 of FIG. 4;

FIG. 6 is a detail section on line 6—6 of FIG. 4;

FIG. 7 is a detail section on line 7—7 of FIG. 4;

FIG. 8 is an exploded perspective of the parts shown in FIG. 7;

FIG. 9 is a fragmentary section, like that of FIG. 4, showing the medial parts shown in FIG. 2;

FIG. 10 is a detail section on line 10—10 of FIG. 9;

FIG. 11 is a detail section on line 11—11 of FIG. 9;

FIG. 11a is an exploded perspective of certain of the parts shown in FIGS. 9 and 11;

FIG. 12 is a fragmentary section, similar to those of FIGS. 4 and 9, showing the lower parts shown in FIG. 2;

FIG. 13 is a fragmentary horizontal section on line 13—13 of FIG. 12;

FIG. 14 is a fragmentary elevation in the aspect indicated by line 14—14 on FIG. 12;

FIGS. 15, 16 and 17 are schematic sectional elevations in an aspect from the left in FIG. 2 and showing operating parts in their different typical positions; and

FIG. 18 is a view similar to FIG. 13 showing the gate in a position such as at D in FIG. 1.

FIG. 1 shows in plan, more or less schematically, the various positions into which the gates of the load divider may be placed. The gates, each preferably of approximate half car interior width, are carried to be raised and lowered and to swing on vertical carrier shafts that are carried on upper and lower rails at the car side walls. FIG. 1 indicates the lower pair of those side-wall rails 40 and the central floor rail 42 to which the lower corners of the swinging edges of the gates are locked when in their positions transverse of the car length. Although at present it is contemplated that a full complement of gates for a car will consist of two pairs—four gates—any desired number may be used. FIG. 1 indicates various typical gate positions. At B and C two gates make up a complete transverse divider wall; at A a gate at one side of the car is shown in staggered relation to that at C; at D a gate is shown stored against the car side wall 44; and at E stored against end wall, or bunker wall, 46. The several gates and their suspensions are duplicates; the following descriptions of one apply to all.

FIGS. 2 and 3 show the general relation of a gate A to its carrier rails and vertical carrier shaft 50. Shaft

50 extends vertically between upper longitudinal rail 52 and lower longitudinal rail 40, located respectively under the car roof 54 and on or recessed into the car floor structure 56, close to side wall 44. The floor structure as here shown includes a lading floor or rack 58 above the car floor proper 60, and lower rail 40 is mounted on floor 60 with its upper surface flush with the lading rack. The rack is commonly made up of sections that may be hingedly pivoted to lower rail 40, as indicated at 62, to be swung up against the side wall, or against a gate in position D, for floor cleaning. The location of hinge pivot 62 at the inside of rail 40 is such that the floor rack sections may be swung up to vertical position against the then inside face of a gate or gates stored in position D against the side wall. As shown more particularly in FIG. 12, the location of hinge pivot 62 relative to rack 58 is such that when the rack is swung up its then vertical outer surface lies in a plane somewhat inward of the inner face 66 of rail 40. And, as will be explained later, the inner face of a gate, in position D against the car side wall, lies outward of rail face 66.

Carrier shaft 50 has upper and lower toothed gears or sprockets 70 and 72, of equal pitch diameters, rigidly affixed at its upper and lower ends. These sprockets meshingly engage, respectively, in longitudinally spaced gear-rack openings 74 and 76 (FIGS. 4, 5 and 12, 13) in the outer side flanges 78 and 80 of upper and lower rails 52 and 40. It will be understood that upper rail 52 with its spaced gear-rack formation extends longitudinally of the full interior length of the car, as does the lower rail 40 with its gear-rack formation. Carrier shaft 50 may be moved longitudinally through the whole length of the car interior and its rail meshing gears maintain it at all times in a vertical position.

Carrier shaft 50 is supported, preferably by suspension at its upper end, by a thrust bearing unit 90 (FIG. 4) attached to the shaft's upper end and having a freely rotatable flange 92 that rides the outer edge 95 of rail flange 94. The under face 93 of flange 92, preferably hardened, is conical at an angle of about 4 or 5 degrees to a normal of its axis and that of shaft 50; that face riding the upper surface of 95, as shown in FIG. 4. As here shown upper rail 52 is made up of an outer angle section 96, with its gear-rack flange 78, an inner angle section 100, and the horizontal flange plate 94, all welded together and secured to the car roof structure as by the bolts shown at 102. Flange plate 94 projects laterally inwardly of the flange 101 of angle section 100 and has, throughout its length, longitudinally spaced openings 104 outward of flange 101, for purposes that will presently appear. Flange 92 is formed as a part of the freely rotatable member 91 that forms the outer cylindrical casting for thrust bearings 89 mounted in supporting relation on shaft 50. That rotatable casing 89 rides the outer edge of flange portion 95, holding gear 70 in mesh with its rack formations 74. It also functions, along with the lower gear 72 to take the weight couple of the gate when the latter in a transverse position is not otherwise supported at its swinging edge, as it is not when, for instance it is raised from the position of FIG. 2. The couple resulting from the fact that the gate is then only supported on shaft 50, is then taken by 91, at the upper end of shaft 50, bearing against 95, and by the lower gear 72 bearing against its rack formation flange 80 as a roller taking a horizontal load. With the gate in any raised transverse position, lower gear 72 is thus held in mesh. In any gate position, such as D in FIG. 1, where gear 72 is not thus pressed into mesh, shaft 50 riding the outer edge of lower rail flange 111 holds it sufficiently well in mesh.

Lower rail 40, as here shown (FIG. 12) is made up of a lower channel section 106 and upper angle sections 108 and 110 welded to the channel's upwardly extending flanges. The upper horizontal flange 111 of angle 110 has, throughout its length, longitudinally spaced perfora-

tions 112 (FIGS. 3, 12 and 13). FIG. 2a shows, schematically, that the spacings of upper rail perforations 104 and lower rail perforations 112 are equal, and that the several pairs of upper and lower perforations are in vertical alinement. The longitudinal gap or slot 113 between the opposed edges of the upper flanges of angles 108 and 110 not only allows shaft 50 to be moved longitudinally of the car but also has other functions to be explained.

The general features of structure and suspension of a gate A are shown in FIGS. 2 and 3. The body of the gate structure is made up of a series of vertical channel elements 120 welded together at their over-laps shown in FIG. 3 and welded to an upper horizontal element 122 and a lower element 124 indicated in FIG. 12. The swinging vertical gate edge (to the right in FIGS. 2, 3 and 12) is finished off with a welded channel formation 126, and the vertical pivoted edge (left in those figures) also has a welded vertical channel formation 128 and a boxing or housing formation 130 that encloses certain operating parts, to be described.

The gate is freely pivoted on carrier shaft 50 to be swung about its vertical axis. As here shown the gate has an upper journal block 134 at its upper edge, and a lower journal block 136 at its lower edge, freely journaling the gate to be swung and raised and lowered on the shaft and freely allowing shaft rotation, regardless of the position of the gate, when the gate and carrier shaft are moved longitudinally along the upper and lower rails. Further details, particularly those associated with the lower journal block will be later described. The gate journalings on shaft 50 not only allow those freedoms of gate swinging and shaft rotation, but also allow the gate to be shifted vertically on the shaft between a lowered and a raised position.

FIGS. 2, 4 and 12 show the gate in lowered position extending transversely of the car—in such a position as at A, B or C in FIG. 1. The lower foot structure 142 that carries the bearing block 136 carries a fixed locking pin 140 projecting below the gate foot 142 which, in that lowered position, rests on the upper apertured flange 111 of rail angle 110. In that position the projecting pin 140 enters a rail perforation 112.

Center rail 42 (FIGS. 1, 2, 3 and 12) has two longitudinal series of spaced perforations 143 and 144 in its upper flange 146 which is also flush with the car floor formation (with the lading rack as shown here). As indicated in FIG. 1 and shown in FIG. 3, the spacings of 143 and 144 are the same as the spacings of apertures 112 in the lower side rails 40, and the pairs of those several apertures are in transverse alinement. With the gate in transverse lowered position, another projecting locking pin 150 at the swinging edge of the gate, enters the center rail perforation 143 or 144 that is in transverse alinement with the side rail perforation that pin 140 enters. Pin 150 projects below a gate foot 152 which then rests on the upper surface of rail 42.

With the gate in the lowered, transverse position, a third locking pin 160 (FIGS. 2 and 4) is projected up from the upper edge of the gate in proper spaced relation to carrier shaft 50 to enter the upper rail perforation 104 that is vertically alined with the lower rail perforation 112 that pin 140 has entered. As FIGS. 5 and 13 indicate, the gate thickness is centered on carrier shaft 50 and pins 140, 150 and 160 are centered on that thickness.

Upper locking pin 160 is formed as the upper end of a locking bar 162 vertically slidable in guides 163 on the gate. Bar 162 has a lower extension 164 coupled to it at 166 (FIGS. 4, 7 and 8) by a coupling involving a T-head 168 in slot 170; that coupling allowing a small amount of mis-alinement of 162 and 164 so that 162 and the mechanism 174 at the lower end of 164 will be free from binding during their vertical sliding movement on the gate.

Referring now more particularly to FIGS. 9-11, the lower end of extension 164 carries a unit 174 that has a block 178 that is externally grooved as at 182 to engage

vertical guide ribs 180 on the inner faces of the flanges of channel 128 (FIG. 11). An operating handle 184 is pivoted on that block and at 186 is pinned to the lower end of a hanger link 188 that is hung more or less loosely at its upper end at 190 from a member 192 incorporated in the gate structure between channel 128 and outer box 130. A turn buckle adjustment at 194 provides for length adjustment of link 188 to adjust the elevations of 174 and locking bar 162 and its pin 160 relative to the gate.

As shown in FIGS. 9 and 11, block 178 has a bore carrying a tubular ferrule 200 which projects its end beyond the block—to the left in those figures. The hub end of handle 184, at 202, encircles the projecting end of the ferrule and preferably has a roller bearing mounting 204 on it. A plunger 206 is pressed outwardly in the ferrule by a spring 208 and has a rounded head 210 that projects out through a cap plate 212 that holds the handle hub on the ferrule and the plunger in the ferrule.

In the lowered gate position shown in the figures so far referred to, handle 184 hangs down from block 178. In that position of the parts, with the pin connection 186 directly below the axis of 174 and plunger 206, its head 210 is spring pressed outwardly into an angle walled groove formation 214 carried by the lower end of supporting link 188. In FIG. 9, handle 184 swings in a plane normal to that of the figure—normal to the plane of the gate. With the handle down, plunger head 210 is pressed into groove formation 214, yieldingly locking the parts in that position.

When the handle is swung up, formation 214 is moved laterally relative to 210, forcing 210 back out of 214. The handle then can be swung freely through 180°, in either direction, about the axis of 174, moving the pin connection 186 to a point above that axis and consequently moving block 174, and its connected parts 164, 162 and 160, down relative to the gate. On return of the handle to the depending position of FIG. 9, sloping wings 216 of the groove formation force plunger head 210 back, to enter 214 as it moves to that final position. In that handle position, 174 and locking pin 160 are in their raised position relative to the gate.

Carrier shaft 50 (see FIG. 4) carries a collar unit 220 made up of a supporting collar 222 fixedly mounted on the shaft, and an upper unit 224 rotatably supported by bearing 226 on 222. In the position of the parts shown in FIG. 4, with locking bar 162 up, a foot member 228 carried by 162 is at a predetermined distance above 224. Downward movement of 162, caused by upward swinging of handle 184, first moves locking pin 160 down out of the upper track perforation 104. When 160 has moved down to clear flange 94 by a suitable distance, foot 228 moves down on support collar 224. Further downward movement of 162 and 228 relative to the gate, then raises the gate, which is then suspended on carrier shaft 50, via 228, 162 and 164 etc.

Those movements of the handle, the upper locking pin 160, and the gate, are illustrated in FIGS. 15-17. FIG. 15 shows the parts in the positions of FIG. 2, with the gate down resting on the floor rails, its lower locking pins engaging in the perforations of those rails, and with upper locking pin 160 in its upwardly projected position engaging a perforation in upper rail 52. Handle 184 is in its depending position where it is yieldingly locked as shown in FIGS. 9 and 11.

It is to be noted that the handle can be swung up in either direction from its depending position where it is completely housed within the gate structure between the two opposite gate faces. FIGS. 9 and 11 show the spacing, in the nature of a vertical slot, 236, at each face of the gate between housing 130 and channel 128, allowing manual access to handle 184 from either side of the gate and allowing the handle to be swung up in either direction. Thus, whichever face of the gate may be against a car wall, or against another gate, the handle may be swung up at the other gate face.

FIGS. 15-17 show the handle being swung up in one of

those directions. As the handle is swung from the position of FIG. 15 to that of FIG. 16, the downward movement of the unit 174, and bars 164 and 162, moves upper locking pin 160 down to clear flange 94 of upper track 52, and moves foot 228 down onto support collar 224. In this position the gate still rests on the lower floor rails with its lower locking pins still engaging those rails, as is shown for locking pin 140 in FIG. 16. In that position upper locking pin 160 has been withdrawn from perforation 104 in upper track flange 94, and clears that flange by a distance designated "a" in FIG. 16. That clearance distance is greater than the distance, designated "b" in FIG. 16, that the lower locking pins, as 140, have to be raised to rise out of the lower track perforations and to clear the upper surfaces of the lower floor tracks and the car floor.

Further upward swinging of handle 184 toward vertical position, as indicated in FIG. 17, with foot 228 resting on support collar 224, then raises the whole gate and with it the locking bar 162 and pin 160, to such a position as shown in FIG. 17, with the lower fixed locking pins, as 140, clearing the lower floor tracks, and with the upper pin 160 still clearing the perforated flange 94 of upper track 52.

In that position the gate is supported solely on carrier shaft 50. The carrier shaft, carrying the gate, may then be moved longitudinally of the car along the upper and lower wall tracks to any desired position. And, in any such position of the carrier shaft, the gate may be swung around the shaft to lie against the car side wall, as in position D of FIG. 1. The gate may then be lowered by returning handle 184 to its depending and locked position of FIG. 15. If the gate is still in transverse position it will then be locked as has been described.

On lowering the gate in position D, its two fixed lower locking pins 140 and 150 enter the longitudinal slot 113 of lower rail 40. As has been remarked, the carrier shaft 50 and the two lower locking pins 140 and 150 are located in one vertical plane—the central vertical plane of the gate. And, as comparison of FIGS. 12 and 13 (to the same scale) will show, the gate half-thickness, designated "c" in FIG. 13, is less than the lateral distance from the center of rail slot 113 to the inner face 45 of side wall 44, and also less than the lateral distance from the slot center to the inner face 66 of rail 40. FIG. 18 also shows that directly. Consequently, the lower gate pins 140 and 150 can enter rail slot 113 when the gate is lowered in position D. The gate will then be supported by its feet resting on the upper face of lower rail 40, and held from swinging; and, with its then inner face outward of rail face 66, the floor racks 58 may be thrown up against it. When handle 184 is finally thrown to its lower locked position with the gate in position D upper locking pin 160 is again projected upwardly freely into the open, downwardly facing channel of upper track 52.

To lock the gate from movement longitudinally of the tracks in position D, two other locking pins 240 are provided, as shown in FIGS. 13, 14 and 18. These are mounted in the foot structure 142 which carries the bearing block 136 and the fixed locking pin 140. Pins 240 are mounted to slide vertically in 142, their downward projection below that foot member being limited to a projection approximately equal to that of fixed locking pin 140. As here shown, pins 242 limit that downward projection.

In the transverse position of the gate, pins 240 may ride the upper surface of rail 40, as shown in FIGS. 13 and 14. In such a position as that of D in FIG. 1, one or the other of pins 240, depending on the direction in which the gate projects horizontally from carrier shaft 50, may drop into one of the spaced perforations 112 of rail 40. FIG. 18 illustrates that, with one of those pins, 240a, dropping into a track perforation 112, and with fixed pin 140 riding in the track slot 113. That

figure also shows how the then outer face A1 of the gate lies not outward of track 40, while the gate inner face A2 is outward of the inner face 66 of the track.

Raising the gate to free it from such a position as D involves the same raising operations as have been explained in connection with FIGS. 15-17. The gate may then be moved and swung to any desired transverse or other position. In any such selected position, lowering and locking the gate involves operation in reverse of the raising operations. The elevated gate, put in the desired transverse location, is then as shown in FIG. 17, with handle 184 up. On lowering the handle to the position of FIG. 16, the whole gate assembly is lowered, the gate then resting on the lower tracks with its lower locking pins in the lower track perforations.

Further lowering of handle 184 then projects upper locking pin 160 finally to its position of FIG. 15 with the pin engaging in the appropriate upper track perforation. Pin 160 is tapered, as shown in other views, so as to enter the perforation without having to be accurately aligned with it. The upper end of locking bar 162 is shouldered at 163 at the base of pin 160. Supporting link 188 is adjusted at 194 to such length that, on final movement of handle 184 to the latched position of FIG. 15, shoulder 163 is forced up against the under face of track flange 94. Due to the fact that connecting pin 186 is then approaching dead center with relation to the axis of 174 and the extents of 164 and 188, shoulder 163 is easily forced up with considerable pressure on the track flange. With the handle then finally latched in its position of FIG. 15, the gate is securely locked down with all its locking pins fully engaged.

The gate can only be held in its raised position by manual force. In any position of handle 184 between the position of FIG. 16 and the ultimate position beyond that of FIG. 17, the handle must be held up to hold the gate up. In the ultimate gate raising position the handle comes up against the bracket 192 that supports the upper end of link 188, with the handle then in such a position as indicated in broken lines at 184a in FIG. 17. Hand-holds such as indicated at 250 in FIGS. 17 and 2, are located between the opposite faces of the gate in such positions that the handle may come up against or close to them. With the handle close to vertical in its upper position the weight of the gate is then easily supported by one-handed grasping of the handle and hand-hold, and the gate is then easily swung or moved. But the gate cannot be carelessly left in its raised position to swing freely and be liable to damage by car swaying, etc. If an operator releases the handle in any gate position, the gate will immediately drop to rest its lower edge or locking pins on the car floor if not into rail apertures, so that it then cannot swing freely. That automatic dropping action is insured by the fact that the handle in its upper position cannot reach the vertical, dead center, position with relation to the pivots at 174, 186 and 190.

The several tracks are conveniently made up of sections of convenient length, which may be secured together endwise in any suitable manner, as by the lug-and-bolt connection 250 shown in FIG. 3. To accommodate variations of interior car lengths, the track apertures at their ends at the car end wall, or bunker wall, may be somewhat elongated, as is shown at 142a in FIG. 3, to allow a gate to be stored directly against the wall.

We claim:

1. In load-divider structure for goods containing compartments that are defined by a floor and a side wall; the combination of rail means including upper and lower rail structures extending lengthwise adjacent the side wall in parallelism to the floor, a carrier shaft extending between and longitudinally translatable on said rail structures in vertical position, a vertically and horizontally extending gate structure having one vertical edge pivoted on said carrier shaft, said lower rail structure having a longitudinal series of spaced recess formations and also a longitudinally upwardly opening slot, said carrier shaft being cooperatively received at its lower end by said slot, another series of spaced recess formations carried by the floor on a longitudinal line parallel to and laterally spaced from said lower rail structure, locking elements carried at the lower edge of the gate structure, one near its pivoted edge and another outwardly spaced from its pivoted edge, said locking elements adapted to enter respectively the first and second mentioned recess formations when the gate structure is in a transverse position, and said outwardly spaced locking element adapted to enter said lower rail slot when the gate structure is in longitudinal position over said lower rail.

- 15 2. The combination defined in claim 1 and also including a third locking element carried at the lower edge of the gate and adapted to enter a lower rail recess when the gate is in longitudinal position over said lower rail.
3. In load-divider structure for goods containing compartments that are defined by a floor and a side wall; the combination of rail means including upper and lower rail structures extending lengthwise adjacent the side wall in parallelism to the floor and each embodying a longitudinally extending gear-rack formation, a vertically extending carrier shaft extending between the upper and lower rail structures, gears of equal pitch diameters fixedly mounted on the carrier shaft and held by the rail structures in meshing engagement, respectively, with the rack formations of the two rail structures, a vertically and horizontally extending gate structure having one vertical edge journaled on the carrier shaft to allow rotation of that shaft and vertical translatable and swinging movements of the gate on and about said shaft, longitudinally spaced recess formations associated with the floor, a projection on the lower edge of the gate structure adapted to engage in said recess formations upon lowering of the gate structure, a locking bar mounted on the journaled edge of the gate structure for vertical movement thereon, a series of longitudinally spaced recess formations associated with said upper rail structure, a locking pin on the upper end of the locking bar adapted on upward projection to enter said recess formations, a manual operating handle mounted on the journaled edge of the gate for swinging movement in a plane normal to that of the gate, and connective means whereby swinging operation of said handle conjunctively causes vertical movement of the gate on said shaft and vertical movement of said locking bar and pin on the gate.
4. In load-divider structure for goods containing compartments that are defined by a floor and a side wall; the combination of rail means including upper and lower rail structures extending lengthwise adjacent the side wall in parallelism to the floor and each embodying a longitudinally extending gear-rack formation, a vertically extending carrier shaft extending between the upper and lower rail structures, gears of equal pitch diameters fixedly mounted on the carrier shaft and held by the rail structures in meshing engagement, respectively, with the rack formations of the two rail structures, a vertically and horizontally extending gate structure having one vertical edge journaled on the carrier shaft to allow rotation of that shaft and vertical translatable and swinging movements of the gate on and about said shaft, said upper and lower rail structures each having a series of longitudinally spaced recess formations and said lower rail structure having a longitudinally extending and upwardly open slot, there being a series of longitudinally spaced recesses associated with the floor on a line spaced from said lower rail structure, a pair of projections on the lower edge of the gate adapted to enter the recesses of the lower rail formation and of the floor upon lowering of the gate on said shaft with the gate in a transverse position, at least one of said projections being adapted to enter said lower rail slot upon lowering the gate in a longitudinal position over said

lower rail, an upwardly projectible locking pin on the upper edge of the gate adapted to be projected up into the recesses of the upper rail structure, and manually operable means carried by the gate structure adapted to cause vertical movement of the gate on said shaft and vertical movement of said locking pin on the gate.

5. The combination defined in claim 4 and also including a third projection on the lower edge of the gate adapted to enter the lower rail recesses upon lowering the gate in said longitudinal position over said lower rail.

6. In load-divider structure for goods containing compartments that are defined by a floor and a side wall; the combination of rail means including upper and lower rail structures extending lengthwise adjacent the side wall in parallelism to the floor and each embodying a longitudinally extending gear-rack formation, a vertically extending carrier shaft extending between the upper and lower rail structures, gears of equal pitch diameters fixedly mounted on the carrier shaft and held by the rail structures in meshing engagement, respectively, with the rack formations of the two rail structures, a vertically and horizontally extending gate structure having one vertical edge journaled on the carrier shaft to allow rotation of that shaft and vertical translatable and swinging movements of the gate on and about said shaft, said lower rail structure having a series of longitudinally spaced recess formations and having a longitudinally extending and upwardly open slot, there being a series of longitudinally spaced recesses associated with the floor on a line spaced from said lower rail structure, a pair of projections on the lower edge of the gate adapted to enter the recesses of the lower rail formation and of the floor upon lowering of the gate on said shaft with the gate in a transverse position, at least one of said projections being adapted to enter said lower rail slot upon lowering the gate in a longitudinal position over said lower rail, and a third projection on the lower edge of the gate adapted to enter the lower rail recesses upon lowering the gate in said longitudinal position.

7. In load-divider structure for goods containing compartments that are defined by a floor and a side wall, the combination of rail means including upper and lower rail structures extending lengthwise adjacent the side wall in parallelism to the floor and each embodying a longitudinally extending gear-rack formation, a vertically extending carrier shaft extending between the upper and lower rail structures, gears of equal pitch diameters fixedly mounted on the carrier shaft and held by the rail structures in meshing engagement, respectively, with the rack formations of the two rail structures, a vertically and horizontally extending gate structure having one vertical edge journaled on the carrier shaft to allow rotation of that shaft and vertical translatable and swinging movements of the gate on and about said shaft, a series of longitudinally spaced recess formations associated with the floor, a projection on the lower edge of the gate structure adapted to enter said recess formations on lowering of the gate on said shaft, the upper rail formation having a series of longitudinally spaced recess formations, an upwardly projectible shouldered locking member mounted for vertical movement on the gate and adapted to enter said rail recesses with its shoulder in upward contact with said upper rail formation, and manually operable means carried by the gate adapted to cause vertical movement of the gate on said shaft and to force said locking member up in shouldered engagement with said upper rail formation to thus forcibly hold the gate down with its lower projection in a floor recess formation.

8. In load-divider structure for goods containing compartments that are defined by a floor and a side wall; the combination of rail means including upper and lower rail structures extending lengthwise adjacent the side wall in parallelism to the floor, a carrier shaft extending between and longitudinally translatable on said rail structures in vertical position, a vertically and horizontally extending

gate structure having one vertical edge pivoted on and vertically movable on said carrier shaft, longitudinally spaced recess formations associated with the floor, a projection on the lower edge of the gate adapted to engage in said recess formations upon lowering of the gate, and means carried by the gate and operable to cause raising and lowering of the gate on said shaft, an upwardly projectible locking pin mounted on the upper edge of the gate, said rail means having a series of longitudinally spaced recess formations adapted to be engaged by said locking pin when projected, and means connecting said locking pin with the gate raising and lowering means and operating to project said locking pin in conjunction with lowering of the gate.

15 9. In load-divider structure for goods containing compartments that are defined by a floor and a side wall; the combination of rail means including upper and lower rail structures extending lengthwise adjacent the side wall in parallelism to the floor, a carrier shaft extending between 20 and longitudinally translatable on said rail structures in vertical position, a vertically and horizontally extending gate structure having one vertical edge pivoted on and vertically movable on said carrier shaft, said lower rail structure having a series of longitudinally spaced recess 25 formations and a longitudinally extending and upwardly open slot, there being a series of longitudinally spaced recess formations associated with the floor on a line spaced from the lower rail structure, a pair of projections on the lower edge of the gate adapted to enter the recesses of 30 the lower rail formation and of the floor upon lowering of the gate on said shaft with the gate in a transverse position, at least one of said projections being adapted to enter said lower rail slot upon lowering the gate in a longitudinal position over said lower rail, and a third 35 projection on the lower edge of the gate adapted to enter the lower rail recesses upon lowering the gate in said longitudinal position over said lower rail.

10. In load-divider structure for goods containing compartments that are defined by a floor and a side wall; the 40 combination of rail means including upper and lower rail structures extending lengthwise adjacent the side wall in parallelism to the floor and each embodying a longitudinally extending gear-rack formation, a vertically extending carrier shaft extending between the upper and lower rail structures, gears of equal pitch diameters fixedly 45 mounted on the carrier shaft and held laterally by the rail structures in meshing engagement, respectively, with the rack formations of the two rail structures, a vertically and horizontally extending gate structure having one vertical edge journaled on the carrier shaft to allow rotation of that shaft and for swinging and vertical translatable movement of the gate relative to the shaft, the shaft being vertically supported by said rail means, operable means for supporting and for raising and lowering the gate structure on the shaft, and means for releasably locking the 50 gate structure against swinging movement about the shaft, said means embodying a longitudinal series of recess formations carried by the floor and a projection at the lower edge of the gate structure adapted to engage with the recess formation when the gate is lowered, said raising 55 and lowering means being adapted to raise the gate structure to a position where its lower projection clears the floor and said recess formations to allow free swinging of the gate structure.

60 11. The combination defined in claim 10 in which said 65 series of recess formations is located on a line laterally spaced from the lower rail structure, said lower rail structure also carrying a second longitudinal series of recess formations, and a second projection at the lower edge of the gate structure adapted to engage one of the last mentioned recess formations when the gate structure is lowered and adapted to clear said lower rail structure when the gate structure is raised.

70 12. The combination defined in claim 11, and including 75 a second longitudinal rail structure mounted on the

11

floor and laterally spaced from said lower rail structure, and in which said first mentioned recess formations are in said last mentioned, floor mounted, rail structure.

13. The combination defined in claim 10 and also including an upwardly projectible locking pin mounted on the upper edge of the gate structure, said upper rail formation having a series of longitudinally spaced recess formations adapted to be engaged by said locking pin when projected, and means connecting said locking pin with the gate raising and lowering means and operating to project said locking pin in conjunction with lowering of the gate structure.

14. The combination defined in claim 10, in which said lower rail structure is carried by the floor and has a series of longitudinally spaced recess formations and a longitudinally extending and upwardly opening slot, and said first mentioned floor-carried series of recess formations embodying a series of longitudinally spaced recesses on a longitudinal line laterally spaced from said lower rail formation, there being a second projection at the lower edge of the gate structure adapted to engage with the recess formations of the lower rail when the gate structure is lowered, and one of said projections adapted to enter

12

said rail slot when the gate structure is lowered in longitudinal position over said lower rail.

15. The combination defined in claim 14, and also including a third projection on the lower edge of the gate structure adapted to enter a lower rail recess upon lowering the gate structure in said longitudinal position over said lower rail.

16. The combination defined in claim 10, and in which
said means for lowering and raising the gate includes a
linkage embodying three pivotal connections and a man-
ually operable lever, and means for limiting the gate rais-
ing movement of said linkage against reaching a stable
position.
